US00D779203S

(12) **United States Design Patent** (10) **Patent No.:** **US D779,203 S**
(45) **Date of Patent:** **** Feb. 21, 2017**

(54) **PARTS STORAGE CONTAINER**

(71) Applicant: **LF Centennial Ltd.**, Road Town, Tortola (VG)

(72) Inventor: **Terrence P. Kinskey**, Alpharetta, GA (US)

(73) Assignee: **L.F. CENTENNIAL LTD.**, Road Town, Tortola (VG)

(**) Term: **14 Years**

(21) Appl. No.: **29/504,307**

(22) Filed: **Oct. 3, 2014**

(51) **LOC (10) Cl.** **03-01**

(52) **U.S. Cl.**

USPC **D3/294**

(58) **Field of Classification Search**

USPC D3/273, 274, 275, 276, 281, 284, 292, D3/294, 295, 296, 297, 299, 905, 901, D3/903, 205, 203.1, 279, 282, 242, 301, D3/302; D9/418, 420-423; D28/76-78, D28/82-83; D99/28, 34

CPC A45C 5/00; A45C 5/04; A45C 11/00; A45C 11/16

(57) **CLAIM**

The ornamental design for a parts storage container, as shown and described.

DESCRIPTION

FIG. 1 is a perspective view of the parts storage container showing my new design.

FIG. 2 is a perspective view of an interior of the design of FIG. 1;

FIG. 3 is a front view of the design of FIG. 1;

FIG. 4 is a back view of the design of FIG. 1;

FIG. 5 is a left side view of the design of FIG. 1;

FIG. 6 is a right side view of the design of FIG. 1;

FIG. 7 is a top view of the design of FIG. 1;

FIG. 8 is a bottom view of the design of FIG. 1;

FIG. 9 is a perspective view of an alternate embodiment showing a transparent surface;

FIG. 10 is a perspective view of an interior of the design of FIG. 9;

FIG. 11 is a front view of the design of FIG. 9;

FIG. 12 is a back view of the design of FIG. 9;

FIG. 13 is a left side view of the design of FIG. 9;

FIG. 14 is a right side view of the design of FIG. 9;

FIG. 15 is a top view of the design of FIG. 9; and,

FIG. 16 is a bottom view of the design of FIG. 9.

The broken lines are included for purposes of illustrating environment and form no part of the claimed design.

1 Claim, 12 Drawing Sheets
